UNITED STATES PATENT OFFICE.

FREDERICK E. MARKERT, OF NEW YORK, N. Y., ASSIGNOR TO JOHN BOYLE & COMPANY, INCORPORATED, OF NEW YORK, N. Y., A CORPORATION OF NEW YORK.

FASTENING DEVICE.

1,395,443.

Specification of Letters Patent.

Patented Nov. 1, 1921.

Application filed January 19, 1921. Serial No. 438,398.

To all whom it may concern:

Be it known that I, FREDERICK E. MARKERT, a citizen of the United States of America, residing at Number 579 East 161st

5 street, borough of the Bronx, city and State of New York, have invented certain new and useful Improvements in Fastening Devices, of which the following is a specification.

10 This invention relates to improvements in separable fastening devices and is especially adapted for use as an awning fastener, but is also capable of being used as a fastener for other devices made of flexible material 15 having reinforced edges and likely to be subjected to heavy strain and hard usage such as carriage curtains, door hangings, and the like.

It is an object of the invention to provide 20 a device of the character described which will be simple, and, therefore, economical in its construction, but at the same time thoroughly practical and reliable as a means for accomplishing its intended purpose.

25 In the drawings illustrating certain forms of the invention,—

Figure 1 is a view in cross section, showing the invention applied as an awning fastener, as a means for securing the top 30 of the awning to the head of a window frame.

Fig. 2 is a view of the same in front elevation.

Fig. 3 is a view of the blank from which 35 the fastener, illustrated in Fig. 1, is made.

Fig. 4 is a perspective view of the same form of the invention, the prongs having been cut and bent in readiness to be secured to the edge of the awning or other device 40 to which the fastener is to be applied.

Fig. 5 is a side view of the fastener of the form illustrated in Fig. 1, the edge of the article to which it is attached being shown in cross section.

45 Fig. 6 is a face view of a modified form of the fastener as secured to the reinforced edge of an article to be supported.

Fig. 7 is a section on the line 7—7 of Fig. 6.

50 Fig. 8 is a face view of the fastener illustrated in Fig. 6, prior to its application to the edge of the article to be supported.

Fig. 9 is a perspective view of the fastener illustrated in Fig. 6, the prongs being bent 55 in readiness for attachment.

Fig. 10 is a face view of a fastener of a second modified form, the same being illustrated as applied to the article to be supported.

Fig. 11 is a section on the line 11—11 of 60 Fig. 10.

Referring more particularly to Figs. 1 to 5, the preferred form of the invention will first be described as applied to an awning 20 having a fold at 21 inclosing a reinforcing 65 element 22.

In Figs. 1 and 2, a fastening device 23, which may be made of steel or any other appropriate material, is provided with a longitudinal slot 24 adapted to be passed 70 over a screw-eye 25 secured in a head 26 of a window frame.

The fastening device is also provided with prongs 27, 28 and 29 (Fig. 4), by which the fastener may be secured to the edge of 75 the awning. The fastener is also provided with a notch 30 in the upper wall of the slot 24, the prong 29 being formed of material cut from the slot 24 and notch 30, as indicated in broken lines in the blank, 80 Fig. 3.

To secure the fastening device to the awning, the prongs 27, 28 are passed through the fabric just below the reinforcing strip, and turned down against the surface with 85 their points directed toward the margin. The prong 29 is at the same time passed over and around the margin of the awning and bent down against its surface with its end directed away from the margin. In 90 this manner, the fastening device is very firmly and positively secured to the edge of the awning, the strain being distributed over a considerable portion of the same by means of the inclosed reinforcing element. 95

To apply the fastening device to the head of the window frame, the screw-eye 25 is given a quarter turn to a horizontal position. The slot 24 is then passed over the screw-eye and the screw-eye returned to 100 the position illustrated in Figs. 1 and 2. The notch 30 drops over the shank of the screw-eye and forms a satisfactory centering means, capable of preventing undesirable endwise movement of the attached 105 awning.

In Figs. 6 to 9, inclusive, is illustrated a modified form of fastening device 23' having prongs 27', 28' corresponding to the prongs 27, 28 of Fig. 4. In this form, how- 110

ever, in place of the prongs 29 there is provided a prong 29' cut from the lower part of the blank (Fig. 8), and turned upwardly against the body of the fastener, and forwardly as illustrated in Fig. 9, in readiness to be passed over the margin of the awning. This form of the device is also provided with a slot 24' and notch 30' corresponding to the slot and notch of the form illustrated in Fig. 4.

The device in the form illustrated in Fig. 9, is attached to the edge of an awning 20', and the prongs turned down against the part inclosing the reinforcing element 22', as illustrated in Figs. 6 and 7. It is then adapted for attachment to the screw-eye or other appropriate means of support, in exactly the same manner as has been described with reference to the form illustrated in Figs. 1 and 2.

In Figs. 10 and 11 is illustrated another modified form, which differs from that illustrated in Figs. 1 to 5, inclusive, only in that the fastening member is provided with a circular opening 31 adapted to receive a rope or cable as a means of support, instead of the screw-eye illustrated in Figs. 1 and 2. It may be observed that in this form of the device the prong 29'' is formed from material cut from the hole 31.

It will be apparent that the above-described fastening device, although simple in construction and economical of material, is adapted to serve as a reliable fastener which may be securely attached to the reinforced edge of an awning or other analogous article formed of flexible material, such as fabric or the like.

It will be understood that the invention is not limited in its application to the particular forms herein disclosed, but is intended to include all such other forms and modifications as fall within the scope of the appended claims.

45 What I claim is:

1. The combination, with the reinforced edge portion of an article of the character described constructed of flexible material, of a fastening device of rigid material having a body portion in contact with one face of said edge portion, a prong extending from said body portion through said edge portion at a point removed from the margin and bent down against the other face, with its end extending toward said margin, and another prong extending forwardly from said body portion at said margin, whereby said body portion and prongs firmly embrace and completely surround the reinforcement at the edge of said article.

2. The combination, with the reinforced edge portion of an article of the character

described constructed of flexible material, of a fastening device of rigid material having a body portion in contact with one face of said edge portion, a pair of spaced prongs extending from said body portion through said edge portion at points removed from the margin and bent down against the other face, with their ends extending toward said margin, and another prong extending forwardly from said body portion at said margin, and bent down against the last mentioned face of said edge portion with its end directed away from said margin, the last mentioned prong lying between the spaced prongs of the first mentioned pair, whereby said body portion and prongs firmly embrace and completely surround the reinforcement at the edge of said article.

3. The combination, with the reinforced edge portion of an article of the character described constructed of flexible material, of a fastening device of rigid material having a body portion in contact with one face of said edge portion, a prong extending from said body portion through said edge portion at a point removed from the margin and bent down against the other face, with its end extending toward said margin, and another prong extending forwardly from said body portion over and around said margin and bent down against the last mentioned face of said edge portion with its end directed away from said margin, whereby said body portion and prongs firmly embrace and completely surround the reinforcement at the edge of said article.

4. The combination with an article of the character described, having a folded edge of fabric and a reinforcing member within the fold, of a metal fastening device having a body portion in contact with one face of said edge portion, a prong extending from said body portion through said fabric, back of said reinforcing member, and bent down against the face of said fabric over said member, and another prong extending from said body portion around said margin and bent down against said fabric and the inclosed reinforcing member, whereby said body portion and prongs firmly embrace and completely surround the folded edge of said article and the inclosed reinforcing member.

5. The combination with an article of the character described, having a folded edge of fabric and a reinforcing member within the fold, of a metal fastening device having a body portion in contact with one face of said edge portion, a pair of spaced prongs extending from said body portion through said fabric, back of said reinforcing member, and bent down against the face of said fabric over said member, and another prong extending from said body portion around said margin and bent down against said

- fabric and the inclosed reinforcing member, the last mentioned prong lying between the spaced prongs of the first mentioned pair, whereby said body portion and prongs 5 firmly embrace and completely surround the folded edge of said article and the inclosed reinforcing member.
6. A fastening device for an article of the character described, comprising a blank of 10 suitable rigid material having a slot disposed crosswise thereof adapted to receive
- the head of a support, a notch in one wall of said slot adapted to engage the shank of said support, and attaching means comprising a prong extending from the opposite 15 wall of said slot and formed from material cut partly from said slot and partly from said notch.

In witness whereof, I have hereunto signed my name.

FREDERICK E. MARKERT.
